DESIGN FOR AN ANNOUNCEMENT STAND

Thomas H. Gist, Bloomington, Ill.

Application May 25, 1939, Serial No. 85,201

Term of patent 7 years

To all whom it may concern:

Be it known that I, Thomas H. Gist, a citizen of the United States, residing at Bloomington, in the county of McLean and State of Illinois, have invented a new, original, and ornamental Design for an Announcement Stand, of which the following is a specification, reference being had to the accompanying drawing, forming part thereof.

The single figure is a perspective view of an announcement stand showing my new design.

The opposite side is substantially the same as shown.

I claim:

The ornamental design for an announcement stand, as shown and described.

THOS. H. GIST.
